UNITED STATES PATENT OFFICE.

CHARLES F. MEYER, OF BRIDGEPORT, CONNECTICUT.

SPARK-PLUG.

1,109,004.

Specification of Letters Patent.

Patented Sept. 1, 1914.

Application filed November 9, 1912. Serial No. 730,302.

To all whom it may concern:

Be it known that I, CHARLES F. MEYER, citizen of the United States, and resident of Bridgeport, in the county of Fairfield and State of Connecticut, have invented certain new and useful Improvements in Spark-Plugs, of which the following is a specification.

My invention relates to new and useful improvements in spark plugs for gasoline engines and refers particularly to that class of plug which is designed to be inserted in or removed from the engine cylinders as occasion may require.

It is the purpose of my invention to generally improve and simplify the construction of spark plugs of this class and particularly to produce a plug wherein the insulation or breakable parts thereof may be removed and replaced without the necessity of disconnecting the remainder, or metal portions of the plug; to form the said insulating parts in a simple manner so that they may be produced inexpensively and can readily be assembled with the other parts of the plug.

With these and other objects in view the invention resides and consists in the constructions and novel combination and arrangement of parts hereinafter more fully described, illustrated in the accompanying drawings, and pointed out in the claim here-to appended, it being understood that various changes in the form, proportion, size and minor details of construction within the scope of the claim may be resorted to without departure from the spirit or sacrificing any of the advantages of the invention.

Similar characters of reference denote like or corresponding parts throughout the several figures of the accompanying drawings forming a part of this specification, and upon which,

Figure 1, shows a side elevation of my improved spark plug complete. Fig. 2, is a central vertical longitudinal section of the same. Fig. 3, shows a detached top end and side view respectively, of the upper or outwardly disposed insulating member of the plug. Fig. 4, is a detached plan and side view respectively of the inner porcelain insulating member in which the lower end portion of the centrally arranged contact rod is mounted, and, Fig. 5, is a detached plan and side view respectively of a packing

ring employed intermediate of the outer insulating member and the attached nut for holding the same in place.

Referring in detail to the characters of reference marked upon the drawings 10 represents the body of the plug, the lower end of which is cylindrically formed and provided with an external thread 11 whereby the plug may be removably placed in position in an engine cylinder. A central longitudinal opening 12 is formed in this body to receive the insulating members 13 and 14 which in turn support the metal contact rods 15 and 15^a. The insulating member 14 is provided with an annular shoulder 17 which rests upon the annular flange 17^a surrounding the smaller end of the opening 12 and in a way to allow the reduced extension of said insulation to project beyond the end of the body to insulatively support the sparking end 18 of the metal rod pin 15. The said insulating member 14 is further provided with an annular flange 16 surrounding its upper end portion which rests upon a shoulder 20 formed in the side walls of the opening 12. This construction obviously permits the said insulating member 14 to be conveniently dropped in from the larger open end of the body of the plug and to promptly seat itself upon the said shoulders and against which it is firmly secured through the medium of the connected parts which will further be explained.

The metal rod 15 which is mounted in the upper insulating member 13 is provided with an enlargement 21 that forms a shoulder to support the insulating member 13 and which also engages and is seated upon the head 18^a of the lower rod 15^a. The insulating members are thus supported at a proper distance apart and in a manner which does not allow the said shoulder and head to come in contact with the inner walls of the body. The upper insulating member 13 is provided with an annular peripheral shoulder 22 upon which is mounted the annular packing ring 23. The upper edge of the ring is engaged by the external inclosing nut 24 that is threadably attached to the outer peripheral end portion of the plug body.

A ferrule 25 is suitably secured to the upper end of the insulating member 13 and likewise engages and surrounds the outwardly extended portion of the metal contact rod 15. The said rod at this point is threaded as shown to receive the binding nut

26 whereby a terminal end of a wire connection 27 may be secured to the plug and electrically connected with the metal rod 15 before mentioned. A second sparking pin 3 28 is suitably secured in the lower end of the body of the plug and has its free end portion disposed inward at a right angle so as to terminate adjacent to the free end 18 of the rod 15^a in the usual manner.

10 From the foregoing construction it will be noted that my design of plug is such as will permit of the removal, if desired, of the internal parts of the plug by detaching the nut 26 and without removing the plug proper 15 and whereby the said parts may be conveniently removed, cleaned and replaced, should occasion require.

Having thus described my invention what I claim and desire to secure by Letters Patent is:

21 A spark plug consisting of a casing externally threaded for attachment to the engine casing and provided with an internal shoulder located at the inner end of the casing and a shoulder located medially of the ends of the casing, an insulating member inserted in the casing and having integral shoulders bearing on the shoulders of the casing and having a rounded inner end pro-

jecting through the inner end of the casing 30 and forming a deflecting surface, a sparking pin on the inner end of the casing, a sparking rod extending through the casing and slideable through the insulating member and having its inner end disposed near the end of the sparking pin, a member on said rod bearing against the outer end of the insulating member, a second insulating member surrounding said rod and bearing against said member, a packing sleeve surrounding said second insulating member and projecting slightly from the outer end of the casing, said second insulating member extending outwardly of the casing, a nut 35 threaded externally on the outer end of the casing and bearing against the packing sleeve and adapted to hold the first insulating member seated against the casing shoulders, said second insulating member projecting through said nut, and means for adjusting the rod in the second insulating member.

Signed at Bridgeport in the county of Fairfield and State of Connecticut this 4th day of November A. D., 1912.

CHARLES F. MEYER.
